(57) **CLAIM**

The ornamental design for a cutting tool, as shown and described.

DESCRIPTION

FIG. 1 is a top, front perspective view of a cutting tool showing a first embodiment of our new design.

FIG. 2 is a top plan view thereof.

FIG. 3 is a bottom plan view thereof.

FIG. 4 is a right side elevational view thereof.

FIG. 5 is a left side elevational view thereof.

FIG. 6 is a front elevational view thereof.

FIG. 7 is a top, front perspective view of a second embodiment of our new design.

FIG. 8 is a top plan view thereof.

FIG. 9 is a bottom plan view thereof.

FIG. 10 is a right side elevational view thereof.

FIG. 11 is a left side elevational view thereof.

FIG. 12 is a front elevational view thereof.

FIG. 13 is a top, front perspective view of a third embodiment of our new design.

FIG. 14 is a top plan view thereof.

FIG. 15 is a bottom plan view thereof.

FIG. 16 is a right side elevational view thereof.

FIG. 17 is a left side elevational view thereof; and,

FIG. 18 is a front elevational view thereof.

The broken line showing of the rear portion of the cutting tool in FIGS. 1–5, 7–11 and 13–17 is for illustrative purposes only and forms no part of the claimed design.
